[57] CLAIM

The ornamental design for the table used primarily for
sorting yarn, as shown and described.

DESCRIPTION

FIG. 1 is a top plan view of a table used primarily for
sorting yarn showing my new design;

FIG. 2 is a typical side elevational view of FIG. 1;

FIG. 3 is a bottom plan view of FIG. 1; and,

FIG. 4 is a perspective view of FIG. 1.

FIG. 1

FIG. 3

FIG. 2

FIG. 4
